(57) **CLAIM**

The ornamental design for an elephant-shaped nightlight, as shown and described.

DESCRIPTION

FIG. 1 is a perspective view of an elephant-shaped nightlight showing my design, as viewed from the top and front.

FIG. 2 is a front profile view of the elephant-shaped nightlight showing my design.

FIG. 3 is a back profile view of the elephant-shaped nightlight showing my design.

FIG. 4 is a first side profile view of the elephant-shaped nightlight showing my design.

FIG. 5 is an opposite second side profile view of the elephant-shaped nightlight showing my design.

FIG. 6 is a top plan view of the elephant-shaped nightlight showing my design; and,

FIG. 7 is a bottom plan view of the elephant-shaped nightlight showing my design.

The details shown in broken lines illustrate features that form no part of the claimed design.
